ABSTRACT

A dual diaphragm distributor actuator has a one piece ring member that separates the diaphragms and constitutes a stop to limit movement of one of the diaphragms in both spark advance and retard directions, and the other diaphragm in a spark retard direction, the stop having axially separate sets of radially depending abutments engaged alternately by a control part extending radially from the one diaphragm so as to be straddled by the abutments, the sets having circumferentially spaced arcuate parts alternating circumferentially with the parts of the other set to form a bayonet type assembly of the abutments and control part.

SPARK ADVANCE/RETARD CONTROL SERVO FOR AN INTERNAL COMBUSTION ENGINE

This invention relates to spark advance/retard devices for distributors of spark ignition internal combustion engines.

In a known device now in use, shown and described in U.S. Pat. No. 3,385,275, a rod is movable to advance or retard the spark; a first diaphragm is fixed to the rod and forms a wall of a first chamber; the first chamber is subject to the pressure in the induction system adjacent to the engine throttle valve; a stop is movable between first and second positions to control the limits of axial movement of the rod; there is a second diaphragm to which the movable stop is fixed; the second diaphragm forms a wall of a second chamber and is subject to the pressure in the induction system downstream of the throttle valve; and, each of the diaphragms is resiliently biased to urge them in the opposite direction to that in which they are respectively urged by vacuum in their respective chambers.

In such a device, a two part spacer is located between the diaphragms to hold the diaphragms in contact with the walls of their respective chambers; and, one part of the spacer has an abutment that limits movement of the stop in one direction while the other part of the spacer has an abutment that limits movement of the stop in the other direction.

The two part spacer increases the cost of the device and also involves an extra assembly operation. This invention provides a construction that reduces the cost of the device and provides an easier assembly operation.

According to this invention, a one piece annular spacer is located between the diaphragms to hold or anchor the diaphragms in contact with the walls of their respective chambers; and, the spacer has abutments to limit movement of the movable stop, the abutments consisting of circumferentially and axially separated parts that project radially inwardly and form with projections on the stop a bayonet type joint.

Other features, advantages and objects of the invention will become more apparent upon reference to the succeeding detailed description thereof, and to the drawings illustrating a preferred embodiment thereof, wherein;

FIG. 1 is a cross-sectional view through a device embodying the invention;

FIG. 2 is an end view of part of the device of FIG. 1;

FIG. 3 is a cross-sectional view of the part shown in FIG. 2; and,

FIG. 4 is an end view of a part shown in FIG. 1.

The device comprises a left hand casing 1, a right hand annular casing 3, and a spacer 5 between flanges on the casings 1 and 3. A first diaphragm 7 is clamped between the spacer 5 and the flange of the casing 1; while a second annular diaphragm 8 is clamped between the spacer 5 and the flange of the casing 3.

An assembly of a cup-shaped member 9, an element 11, and a rod 13 is fixed to the center of the first diaphragm 7. A spring 15 is compressed between the casing 1 and cup-shaped member 9 to force the diaphragm 7 and rod 13 rightwardly. The rod 13 projects through the central opening in the casing 3 and is connected to the distributor, and as it is moved axially to the left or right, it advances or retards the ignition. The diaphragm 7 closes the open end of the casing 1 to form a vacuum chamber which is connected by a pipe, not shown, to the induction system at a point upstream of and adjacent to the periphery of the throttle valve, when it is in its engine idle speed position.

The inner radial edge of the diaphragm 8 is clamped between a turned over lip 19 at the inner side of the casing 3. An assembly comprising a cup-shaped member 21 and a control member 23 is attached to the diaphragm 8 by three fasteners 25. A coil spring 27 is compressed between the base of the casing 3 and the member 21 to force the diaphragm 8 towards the left in FIG. 1. The diaphragm 8 seals the end of the casing 3 so that it forms a second vacuum chamber. This chamber is connected by a pipe 29 to the induction system downstream of the throttle valve.

The member 23 is annular and has an inner flange 31 and an outer flange 33. The inner flange 31 is engaged by the member 11 attached to the diaphragm 7. The outer flange 33 alternately engages axially spaced abutments 37a and 37b that straddle flange 33 and are integral with and project inwardly from the spacer 5. The member 23 and abutments integral with the spacer 5 form a bayonet type joint.

The outer flange 33 of stop 23 consists of three arcuate projections 35 (FIG. 4); the radial extent of each one is between the radial extents of the inwardly projecting sections 37a and b. The assembly of the diaphragm 8, stop 23 and cup-shaped member 21 can, therefore, be moved axially towards the spacer 5 with the projections 35 passing between adjacent sections 37. As stated above, adjacent sections 37a and b are axially spaced (FIG. 1); thus section 37a is closer to the diaphragm 7 than the adjacent section 37b. When the projections 35 (FIG. 4) are axially positioned between adjacent sections 37a and 37b, and circumferentially between adjacent abutments 37a, the assembly of the diaphragm 8, stop 23 and cup-shaped member 21 can be rotated circumferentially until each projection 35 overlaps both a section 37a and a section 37b. The axial distance that the projections 35 and hence the stop 23 can move is thus determined by the axial distance between adjacent sections 37a and 37b.

As best seen in FIG. 2, the abutments 37a and 37b consist of three arcuate projections 37a circumferentially spaced equally from one another and alternating circumferentially with three spaced arcuate projections 37b. The abutments a and b depend radially from opposite axial sides of spacer 5, with 37a extending radially inwardly farther than 37b.

It will be seen that the invention provides a spacer 5 formed in one piece and formed with the abutments 37a and 37b and stop 21 as a bayonet type joint. The movement of diaphragm 8 in a leftward or spark advance direction is limited by the stop 37a, and in a rightward or spark retard direction by the stop 37b. The diaphragm 7 can move freely in a leftward advance direction, and is controlled in its rightward retard movement by abutment against the movable stop 23.

I claim:

1. A fluid motor assembly comprising, a housing, a pair of flexible diaphragm members each mounted in said housing for an independent movement relative to the other and each with said housing defining a different vacuum chamber, means connecting each of said chambers to a separate source of fluid varying from a maximum essentially atmospheric pressure level to a minimum sub-atmospheric pressure or vacuum level for reciprocable movement of each of said members as a function of the changes in vacuum acting thereon, spring means biasing each of said diaphragm members towards the other, movable actuating means connected to a first one of said diaphragm members for movement therewith, means on said first diaphragm member engageable at times with the other second one of said members upon movement of said first member in one direction for limiting the movement of said first member in said one direction in a variable manner as a function of the position of said second member, and stop means in the path of movement of said second member providing a limited movement of said latter diaphragm member, said stop means comprising a one piece ring-like member having radially inwardly extending abutment members that are axially spaced with respect to each other and project into the path of movement of said second member for alternate engagement by the second member.

2. An assembly as in claim 1, each of said abutment members comprising a set of circumferentially spaced portions.

3. An assembly as in claim 2, said axially spaced sets having their portions circumferentially alternated with the circumferentially spaced portions of the other set to form a bayonet type assembly.

4. An assembly as in claim 2, including guide means on said second diaphragm member cooperable with said stop means to limit movement in opposite directions of said second diaphragm, said guide means extending radially between the inner and outer radial portions of said abutment portions.
